UNITED STATES PATENT OFFICE.

ISAAC V. ADAIR, OF MACDOUGALL'S, NEW YORK.

WIRE-FENCE-WINDING DEVICE.

SPECIFICATION forming part of Letters Patent No. 519,103, dated May 1, 1894.

Application filed November 7, 1893. Serial No. 490,248. (No model.)

To all whom it may concern:

Be it known that I, ISAAC V. ADAIR, a citizen of the United States, residing at MacDougall's, in the county of Seneca and State of New York, have invented a new and useful Fence-Weaving Apparatus, of which the following is a specification.

My invention relates to a fence weaving apparatus, adapted for use in attaching barbed or smooth wire stays to the parallel strands of a wire fence, and it contemplates the provision of a simple, inexpensive and efficient device of portable size and shape which may be operated conveniently and quickly without the aid of auxiliary tools or appliances.

Further objects and advantages of my invention will appear in the following description, and the novel features thereof will be particularly pointed out in the claim.

In the drawings: Figure 1 is a perspective view of the apparatus embodying my invention, shown in operative position in connection with a fence. Fig. 2 is a detail view of the same.

Similar numerals of reference indicate corresponding parts in both figures of the drawings.

1 designates a frame, preferably rectangular in form, comprising a U-shaped bar, 2, the arms of which are connected by a transverse bar, 3, and the intermediate portion of which is rounded to form a handle 4. The arms of the U-shaped bar are extended beyond the connecting bar, 3, and terminate, respectively, in a rounded yoke, 5, adapted to fit over and bear upon a fence-wire, and a hook, 6, which is adapted to engage the same wire and prevent that end of the frame to which it is connected from being drawn away from the wire, as will be hereinafter particularly explained.

Secured to the connecting-bar, 3, is a stirrup, 7, between the parallel arms of which is rotatably mounted a spool, 8, to hold the wire, 9, for forming the stays; said wire extending through a guide, 10, in one arm of the U-shaped bar adjacent to the yoke 5. Said guide consists of a perforation formed in the arm of the bar 2, substantially in the horizontal plane of the under or inner side of the spool, or that side of the spool from which the stay-wire is unreeled.

In Fig. 1 I have shown the device applied to a fence, as seen when weaving the stays, 55 and referring thereto, 11 indicates the horizontal fence wire or strands with which the yoke 5 and hook 6 are engaged to mount the weaver, rotatably, upon the fence; and 12 represents the stay after being secured in position and coiled at each intersection around the fence-wires.

After applying the device to a wire, as indicated, the extremity of the wire, 9, is held in contact with the fence-wire and the frame 65 is rotated to coil or twist the former around the latter. The tension produced by drawing the wire through the guide, which causes a right-angle bend of said wire, prevents the wire from feeding more rapidly than is desired, and at the same time holds the front end of the apparatus, or that end adjacent to the coil and having the yoke 5, in engagement with the fence-wire, the tendency of the other or rear end of the frame to rise or 70 draw away from the fence-wire being resisted by the hook 6. After the first twist has been formed, to secure the end of the stay-wire, the device is disengaged from the fence-wire, 75 and attached, in like manner, to the next lower or upper fence-wire, and the operation continued as before.

Being simple in construction the twister is not liable to need repair.

The guide perforation is flared toward the 85 spool to enable a barbed wire to pass therethrough with facility.

The above-described arrangement of the wire-guide in the plane of that side of the spool from which the wire extends allows the 90 wire to feed freely and without binding in the guide.

Various changes in the form, proportion, and minor details of construction may be resorted to without departing from the spirit or 95 sacrificing any of the advantages of the invention.

Having thus described my invention, I claim—

In a device of the class described, the com- 100

bination of a frame having parallel arms, one of which is provided with a wire-guide and terminates in a yoke 5, which is adapted to straddle a fence wire or runner, and the other 5 of which terminates in a hook 6, which is adapted to engage under said fence wire or runner to resist an outward pull upon that end of the frame, and a spool journaled within the frame with its axis arranged trans-

verse to the line of the fence wire or runner, to substantially as specified.

In testimony that I claim the foregoing as my own I have hereto affixed my signature in the presence of two witnesses.

ISAAC V. ADAIR.
